Design
No. 20,076

UNITED STATES PATENT OFFICE.

• ZACHARY T. HALL, OF PHILADELPHIA, PENNSYLVANIA.

DESIGN FOR A TOY MONEY-BOX.

SPECIFICATION forming part of Design No. 20,076, dated August 5, 1890.

Application filed June 19, 1890. Serial No. 356,008. Term of patent 14 years.

To all whom it may concern:

Be it known that I, ZACHARY T. HALL, a citizen of the United States, residing in the city and county of Philadelphia, State of Pennsylvania, have invented and produced a new and original Design for Toy Money-Boxes, of which the following is a specification, reference being had to the accompanying photograph, forming part thereof.

10 The leading feature of my design for a toy money-box is the cylindrical body of the same having on the side thereof a grouping of coins of money.

15 Figure 1 represents a perspective view of a toy money-box embodying my design. Fig.

2 represents the wall of the box in primary condition.

Referring to the photograph, A designates the body of a toy money-box, the same being of cylindrical form, with a head at the top and 20 bottom thereof. On the wall of the body is a grouping of coins, as at B.

I claim—

A design for a toy money-box, as shown and described.

ZACHARY T. HALL.
